UNITED STATES PATENT OFFICE.

FREDERICK J. HUBBARD, OF SYRACUSE, NEW YORK.

CAPSULE-HOLDER.

1,148,776.

Specification of Letters Patent.

Patented Aug. 3, 1915.

Application filed December 11, 1914. Serial No. 876,663.

To all whom it may concern:

Be it known that I, FREDERICK J. HUBBARD, a citizen of the United States, and resident of Syracuse, in the county of Onondaga, in the State of New York, have invented new and useful Improvements in Capsule-Holders, of which the following, taken in connection with the accompanying drawings, is a full, clear, and exact description.

10 This invention relates to certain improvements in capsule holders for temporarily gripping and holding breakable medicine capsules or conceals preparatory to extracting the contents therefrom for use in hypodermic injections or other purposes.

For hygienic reasons and safety, the more powerful medicines, such as those which are applied to patients hypodermically, are usually put up and sold to physicians and surgeons in small quantities in hermetically sealed tubes or conceals of glass or other fragile or easily breakable substance and are kept in this hermetically sealed condition until needed for use and are then broken at one end sufficiently to allow the contents to be withdrawn by a hypodermic syringe or needle by which they are injected into the patient without liability of contamination with foreign matter, and in view of the relatively small size of such capsules or conceals, the physicians and surgeons have considerable difficulty in holding them in proper position to extract the contents without liability of dropping them or wasting such contents.

The main object, therefore, of my invention is to provide a simple and comparatively inexpensive device for temporarily holding these conceals while breaking the ends thereof and withdrawing their contents without liability of dropping the same or wasting the contents.

Another object is to enable the whole device to be tilted to different angles to conform to the position or convenience of the user in withdrawing the medicine from the conceal or capsule.

Other objects and uses relating to specific parts of the device will be brought out in the following description.

In the drawings—Figures 1 and 2 are, respectively, a top plan and a side elevation of a capsule holder embodying the various features of my invention, the gripping device being shown by dotted lines in different positions of adjustment, and the capsule being

also indicated by dotted lines as being held by the gripping jaws. Fig. 3 is a vertical sectional view of the same device taken on line 3—3, Fig. 1. Fig. 4 is an elevation partly in section of a modified form of capsule holder in which the gripping device is rigidly secured to its supporting base.

The preferred form of my invention shown in Figs. 1 to 3 inclusive, comprises a supporting base or standard —1— and a capsule holder —2— adjustably mounted thereon, and held in its adjusted position by means of a clamping bolt —3— and hand-nut —4—. The bottom of the standard —1— is relatively broad and adapted to rest upon a table or other suitable support, the upper portion thereof being reduced and provided at its upper end with a transverse bolt opening —5— for receiving the clamping bolt —3— which extends beyond opposite sides of the standard and is provided at one end with a vertical opening —6— for receiving an upright rod —7— forming a part of the capsule holder, the opposite end of said bolt being threaded and engaged by the hand-nut —4—, thus permitting the rod —7— to be drawn tightly against the adjacent side of the standard —1— when the nut —4— is tightened and also permitting said rod to be adjusted vertically when the nut is loosened.

Secured to the upper end of the rod —7— is a clamping plate or head —8— having a V-shape groove —9— transversely in its upper side to form a suitable seat for a capsule or conceal as —a— which the device is adapted to temporarily hold, diametrically opposite sides of the plate or head —8— being provided with recesses —10— for receiving and guiding the opposite arms of a U-shape bar —11—. The upper portion of the bar —11— extends across the open side of the groove —9— above the plate —8—, while the lower ends of its opposite arms are secured to a guide plate —12— having a central aperture —13— through which the supporting rod —7— extends and is free to slide therein. The upper portion as —11'— of the U-shape bar —11— together with the plate —8— constitutes gripping jaws between which the conceal or capsule —a— is yieldingly held by a coil spring —13— surrounding the rod —7— between the plates —8— and —12— and having its opposite ends abutting against said plates, the spring being tensioned to nor-

mally force the gripping jaws toward each other, or rather to force the U-shape bar —11— and its supporting plate —12— together with the gripping member —11'— 5 downwardly to frictionally hold the capsule —a— in operative position.

The bolt —3— is loosely mounted in the aperture —5— so as to permit it together with the capsule gripping device to turn to 10 different angles about the axis of the bolt to bring the capsule into any convenient position to any angle as may be most convenient to the physician, surgeon or other operator. In some instances, however, as 15 shown in Fig. 4, the lower end of the rod as —7— may be rigidly secured in the upper end of a supporting base or standard —1'—, but otherwise, the capsule gripping device is substantially the same as that 20 shown in Figs. 1, 2 and 3. It is also evident that the gripping device including the rod —7— may be turned in the aperture —6— when the nut —4— is loosened. These capsules are usually made of glass or other 25 fragile or easily breakable material and hermetically sealed contents, thereby preventing any possibility of contamination of the medicine with foreign matter.

When it is desired to use the contents of a 30 capsule or conceal, the operator lifts the plate —12— and parts carried thereby by hand until the upper jaw —11'— is raised a sufficient distance above the plate —8— to allow the insertion of the capsule into the 35 groove —9—, whereupon the upward pressure on the plate is relieved and the spring —13— returns it together with the U-shape bar —11— and jaw —11'— until the jaw —11'— engages the periphery of the capsule 40 to frictionally hold it to its seat —9—. One end of the capsule may then be broken off by filing the same at the point where it is

desired to break, after which the contents may be withdrawn by a hypodermic syringe and applied to the patient in the well known 45 manner.

The operation of my invention will now be readily understood by reference to the foregoing description and the accompanying drawing.

It will be noted that various changes may be made in the details of construction of the various parts without departing from the spirit of this invention.

What I claim is:

1. In a device for temporarily holding medicine capsules, a rod having a V-shape jaw on one end, a plate slideable on the rod, a gripping member extending across the open side of the groove attached to said 60 sliding plate, and a spring interposed between said plate and jaw for forcing the jaw and gripping member toward each other to grip a capsule.

2. In a device for temporarily holding 65 medicine capsules or conceal, a rod, a jaw secured to one end of the rod and provided with a groove in its outer end face and with recesses in its opposite edges, a U-shape bar extending across the open side of the groove 70 and having its opposite arms guided in the recesses, a plate slideable lengthwise of and upon the rod and secured to the ends of the bar, and a coil spring surrounding the rod 75 and having its ends abutting against the plate and jaw respectively for forcing the jaw toward the portion of the bar which extends across the groove.

In witness whereof I have hereunto set my hand this 4th day of December 1914.

FREDERICK J. HUBBARD.
